SHEET METAL SEAMING TOOL

Carl R. Schlicht, near La Crosse, Wis.

Application December 9, 1936, Serial No. 114,984

8 Claims. (Cl. 113—56)

One of the main objects of this invention is to provide such a seaming tool which is simple and economical in construction, and which is comparatively easy to operate so as to conserve 5 energy and will at the same time produce a firmly clenched seam.

A further object of this invention is to provide a seaming tool wherein the leverage of a chief operating member, and thereby the force exerted 10 by the jaws on the seam, is gradually and automatically increased as the clenching operation proceeds, so as to produce a maximum of clenching pressure at the final part of each clenching step and provide a firmly clenched seam.

15 Another object of this invention is to provide such a seaming tool wherein the two jaws are differently arranged and are actuated to function differently, so that this tool is adapted for performing different bending operations by reversing 20 its positions on the seam.

Still another object is to provide such an efficient seaming tool which is arranged so that it can be economically built by utilizing several standard and readily obtainable members for 25 providing several of its parts.

These and various other objects and advantages are attained with this invention, as will become apparent from the following description taken in connection with the accompanying drawings 30 wherein the invention is shown in its preferred form of construction, it being apparent that various other forms and arrangements may be resorted to for carrying out the objects and purposes of this invention.

35 In the drawings:

Fig. 1 is a top plan view of my novel seaming tool illustrated in its preferred form of construction.

Fig. 2 is an elevational view of the tool in position 40 on a seam, after completing the first step of the seaming operation.

Fig. 3 is a view similar to that of Fig. 2, but showing the tool in position on the seam at the beginning of the seaming operation.

45 Fig. 4 is an elevational view of the tool on the seam, but shown in its reversed position from that shown in Fig. 2, and at the beginning of the second step of the seaming operation.

Fig. 5 is a view similar to that shown in Fig. 4, 50 with the tool in said reversed position, and when the second step of the seaming operation has been completed.

My invention is illustrated in the drawings in its preferred form of construction, comprising a 55 pair of operating levers 11 and 12 and means 13

connecting them to provide pivotal or hinged movement therebetween. For the sake of economy, these levers are made from suitable lengths of ordinary strong metal pipes; and for the lever connecting means 13 I preferably use a strong leaf hinge, which includes a leaf 15 and a leaf 16. Said levers 11 and 12 are secured, respectively, to the hinge leafs 15 and 16, preferably by welding or securing the two levers in two openings provided in the hinge leaves. 10

The jaw members 17 and 18 of this tool are angle-shaped in cross-section, being substantially in the form of angle plates, which comprise, respectively, the clenching jaw portions 17' and 18' serving as the active jaw portions engaging the 15 seam, and the mounting angle portions 17'' and 18'' whereby the jaw members are connected to the two opposite hinge parts of hinge means 13. One of these jaw members is fixedly connected to a hinge part and its associated lever, while the 20 other jaw member is slidably mounted on the device to provide a sliding movement to it toward and away from its companion jaw member. In this illustrated construction the jaw member 17 has its mounting portion 17'' secured underneath 25 the hinge leaf 15, as by riveting it thereto, and has its clenching portion 17' depending therefrom; while the other jaw member 18 has its clenching portion 18' extending horizontally toward said 30 clenching portion 17', adapted to be movable under hinge leaf 16, and it has its mounting portion 18'' provided with means which connects it slidably with the levers and the hinge means. 35

In the form of construction shown in the drawings the slidable mounting means for jaw member 18 includes a pair of sleeves 19 secured on hinge leaf 16, and a pair of shafts 20 secured to angle portion 18'', as by threading them therein and using locknuts 21 thereon. The shafts 20 are slidable in sleeves 19, and slidable movement 40 is thereby provided to jaw portion 18' toward and away from jaw portion 17', to-and-fro underneath hinge leaf 16.

Means is also provided herein for increasing the 45 clenching force of the levers upon the jaw members during the seaming operation, and in the form illustrated this means includes a collar 22 mounted slidably on lever 11, and a pair of links 23 connected to the collar by pivot pins 24. A clevis or yoke-shaped member 25 is secured to 50 angle portion 18'', by bolts 26 or the like, and this member 25 is pivotally connected to the free ends of said links 23, as by means of pivot pins 24' extending outward from the arms of the yoke member, as best shown in Fig. 1. 55

In operating this seaming tool it is first placed as indicated in Fig. 3, so that the hinge means rests upon the superposed flanges or bent portions 27 and 28 which have been previously provided at the joining edge portions of the sheets of metal 29 and 30 to be connected by the seam. The jaw portion 18' is placed at the outside of the depending portion 28' of the superposed portion 28; and the jaw portion 17' is placed to bear 5 against the opposite edge part of the superposed portions 27 and 28, to serve as the holding jaw. Then, upon moving lever 11 away from lever 12, the links 23 draw jaw member 18 forward and force its jaw portion 18' against the depending portion 28' to bend it underneath seam portion 27, completing the first step of the seaming operation, as illustrated in Fig. 2. The jaw portion 18' served as the active or clenching jaw during this first step, while the other jaw portion 17' served 10 as the holding jaw, and gradually swung downward against the upstanding part 31 of the seam, as shown in Fig. 2. Thus, when slidable jaw portion 18' first bends the over-lapping portion 28' inwardly around the outer edge of portion 27, the heel or angle part of jaw member 17 bears against the opposite edge part of the superposed portions 27 and 28, as shown in Fig. 3, and in the directly 15 opposite direction to the pressure exerted by the bending upper edge part of seam portion 28', where the holding effect of jaw member 17 is at 20 a maximum.

During the movement of the various parts, in performing this first step of the seaming operation, the shafts 20 have slid further into sleeves 35 19; and at the same time, collar 22 has slid downward on lever 11, toward hinge leaf 15. Thus the leverage of lever 11 has been gradually and automatically increased during its operative movement away from lever 12, thereby likewise increasing the force and clenching effect of jaw 18' 40 upon the seam, and more particularly during the final part of each seaming step and at the time when the greatest clenching force is most valuable, to produce a tightly closed seam.

45 The tool is then reversed in its position upon the seam, for performing the next step of the seaming operation, as shown in Fig. 4. The jaw portion 18' then bears against the upstanding part 31 of the seam, and serves as the holding jaw; while the jaw portion 17' bears on the outer edge of the overlapped and superposed portions 50 28, 27 and 28', and serves as the active or clenching jaw. Then, as the tool is actuated by swinging lever 11 away from lever 12, this active jaw 17' 55 and the superposed seam portions are brought down into the position shown in Fig. 5, thereby completing the second step of the seaming operation, and providing a tightly interlocked seam.

It should be noted that in both of these steps of 60 the seaming operation the lever 12 serves as a stationary or holding lever; while lever 11 is moved by swinging it outwardly away from lever 12, thus functioning as the active lever. Likewise note that jaw member 17, which is firmly 65 secured to the swingable lever 11, is swung during both steps of the seaming operation; while jaw member 18 is provided with slidable movement relative to the other jaw member and parts.

I claim:

70 1. A seaming tool comprising a pair of levers and a pair of jaw members, means connecting the levers for relative pivotal movement, means for mounting one of said jaw members fixedly with one of said levers and the said connecting means, means between the second jaw member

and the first said connecting means to mount this jaw member for slidable movement toward and away from said one jaw member, and means operatively connected to the slidable jaw member and being connected with the said one lever 5 to have movement longitudinally thereof, whereby the force applied thru the levers to the jaw members is automatically increased during the seaming operation.

2. A seaming tool comprising a pair of levers 10 and means connecting them for relative pivotal movement, a pair of jaw members one of which includes an attaching portion and a depending jaw portion, means fixedly connecting one of said levers with the said attaching portion, the second 15 jaw member including an upper mounting portion and a jaw portion extending therefrom toward said depending jaw portion, means connecting the said mounting portion operatively with the first said connecting means to provide 20 said second jaw member with slidable movement relative to the first said connecting means, and means operatively connected with the said mounting portion and with the said one lever to operate said second jaw member, thereby adapting the 25 tool for different bending operations by reversing it on the seam.

3. A seaming tool comprising a pair of levers and means connecting them for relative pivotal movement, a pair of jaws and means for mounting one of them fixedly with respect to one lever, means for mounting the second jaw on said connecting means to be slidable relative thereto and to the second lever, and means connected with said second jaw and including a member mounted 35 for longitudinal slidable movement on the said one lever, whereby the force applied thru the levers to the jaws is automatically increased during the seaming operation.

4. The subject matter set forth in claim 3, and 40 wherein the said one jaw has a depending plate-like jaw portion, and the second jaw has a plate-like lower jaw portion extending horizontally toward said depending jaw portion to move toward it and away therefrom, thereby adapting the tool 45 for different bending operations by reversing it on the seam.

5. A tool for seaming sheet metal, comprising a hinge of two pivotal portions, a lever secured to each portion, a jaw firmly secured to one hinge 50 portion, a second jaw, means mounting it slidably on the second hinge portion, and means connected with said second jaw and provided with means embracing one of said levers to be slidable longitudinally thereon, whereby to increase automatically 55 the leverage of said one lever and thereby the force applied thru the levers on the jaws during the seaming operation.

6. The subject matter set forth in claim 5, and 60 wherein the first said jaw has a depending portion, while the second jaw has a lower plate-like portion and its slidable mounting means adapts it to slide inwardly and upwardly toward the hinge during operation and thereby form a tightly clenched seam.

7. A tool for seaming sheet metal, comprising a pair of levers and hinge means having a lever secured to each of its opposite hinge portions, a pair of angle-shaped jaw members, one having an upper mounting portion secured to a hinge portion 70 and lever and also having a relatively broad jaw portion depending therefrom, the second jaw member having a relatively broad jaw portion extending below the hinge means and toward the depending portion, means for mounting 75

the second jaw member on the second hinge portion and provide sliding movement inwardly toward the depending jaw portion and slightly upwardly toward the hinge means, and means connected with said slideable jaw member and being connected with said one lever to move longitudinally thereon, whereby to automatically and gradually increase the leverage of said one lever and thereby the force exerted thru the levers on the jaws during the seaming operation and provide a tightly clenched seam, said tool being adapted for different seaming operations by reversing it on the seam.

8. A tool for seaming sheet metal, comprising a pair of levers and a leaf hinge having a lever secured to each of the hinge leaves, a pair of jaw members, one having an upper mounting portion secured to a hinge leaf and having a plate-like jaw depending therefrom, the second jaw mem-

ber having an upper mounting portion and having a plate-like jaw extending therefrom horizontally toward the depending jaw, slidably connected companion means having one means secured to the mounting means of the second jaw member and having the other means secured at a slant on the second hinge leaf to provide the horizontal jaw an inward and slightly upward sliding movement toward the depending jaw and the hinge, and means including a member slideable on one of the levers also link means connected to said member and to the mounting means of said second jaw member, whereby the force exerted thru the levers on the jaws automatically and gradually increases during the operative movement of the levers, and the tool being adapted for different seaming operations by reversing it on the seam.

CARL R. SCHLICHT.
